UNITED STATES PATENT OFFICE.

DERK VAN DER WOUDE, OF GRONINGEN, NETHERLANDS.

CENTRAL HEATING INSTALLATION.

Application filed August 12, 1924, Serial No. 731,688, and in the Netherlands June 3, 1924.

According to a well known system of heating, the water issuing from the radiators is led into an open space and forced up thence by a pump into the heating boiler. 5 The water delivered under pressure to the radiators is admitted to these latter by being allowed to pass through a narrow opening which is adjustable and adapted to be closed. The radiators themselves are under 10 atmospheric pressure.

It has been observed that for the heating of large groups of dwellings, for which systems of the type are principally designed, these systems have not yielded the results 15 expected, owing to the fact that the delivery pressure varies according to the number of radiators in use, to such an extent that it is necessary to keep a constant watch on the apparatus in order to correct the regulation 20 of the cross sectional area of the passage for the water. As the lowest pressure which is capable of existing should be sufficient to produce a suitable supply of water, the highest was sometimes such that the cross 25 sectional area of the passage became too strongly throttled, which together with the presence of obstructions rendered accurate regulation difficult and often caused a disagreeable noise.

30 In addition to these defects this variation of the delivery pressure also possessed the disadvantage that the heat consumed could not be measured by the quantity of water passing into the radiators.

35 The object of the present invention is to remedy these disadvantages. By the provision of one or more intermediate chambers on the pressure side of the pump, in which chambers a substantially constant 40 pressure is maintained, it is possible to provide a substantially constant delivery pressure to the radiators. For the central heating of a large number of dwellings, it is advisable to employ several intermediate chambers into which the supply pipe opens and which supply the radiators. These chambers are preferably constructed in the form 45 of float reservoirs which communicate with the external air and in which the level of the liquid is maintained automatically at a 50 constant height. In the case of the heating of a comparatively small number of dwellings or large buildings, a single intermediate chamber may be used, which is placed in an 55 elevated position and may then be open. This single intermediate chamber may be

provided with means for heating the water therein, in which case a separate boiler may be dispensed with.

The drawings show examples of two constructional forms of the invention above described. 60

The figure in the drawing shows diagrammatically an installation comprising several 65 intermediate chambers.

In the drawing, 1 is the heating boiler from which the hot water is conveyed through a pipe 2 to the points of consumption. From this pipe 2 lead pipes 3 which supply the hot water to the radiators 4, the 70 water being discharged from said radiators through pipes 5 and a return pipe 6 into an open reservoir 7 whence the water is withdrawn by a pump 8 for the purpose of feeding the boiler. 75

The vertical pipes 3 open into open chambers 9 in which the level of the water is regulated by floats 10 independently of the pressure existing in the pipes 3. From the float chambers 9 the hot water is led through 80 pipes 11 to the radiators 4. The supply of water to each radiator is regulated by a throttling device 12, placed in the outlet pipe of the radiator. This position of the throttling device has the advantage that any 85 dirt or impurities which may be carried along by the hot water are enabled to settle down at the lower part of the radiators and do not choke up the throttling device 12.

The radiators are also connected at their 90 lowest points to the outlet pipes 5 by cocks 13 which are normally closed. These cocks 13 are opened only when the radiators corresponding thereto are to be put out of operation for the time being. The cocks 14 in 95 advance of the radiators are then closed, the water exhaust from the radiators through the cocks 13 and carries with it the dirt and impurities which may have settled down at the lower part of the radiators. If the entire heating installation of a dwelling is to 100 be cut out, the cocks 14 are also opened while the cocks 15 on the supply pipes are closed. To enable these latter pipes to be emptied the cocks which permit communication 105 between the pipes 3 and the return pipe 6 by means of auxiliary pipes 17 are also opened.

In the installation constructed according 110 to the present invention the pressures remain practically constant on the delivery and outlet sides. It is thus possible to measure

by the aid of water meters the quantities of water passing into the radiators and to reduce therefrom the heat consumed.

Having now particularly described and ascertained the nature of my said invention and in what manner the same is to be performed, I declare that what I claim is:—

A central water heating installation comprising radiators, an open reservoir placed below certain of said radiators, a radiator return pipe opening into said reservoir, a water pump, a pipe leading from the open

reservoir to the suction side of said pump, chambers elevated with respect to the radiators which they serve, pipes leading from the pressure side of the pump to said chambers, pipes leading from each chamber to the corresponding radiators below, means for heating the water fed by the pump to the radiators, and means to maintain a substantially constant level in each chamber.

In testimony whereof I affix my signature.

DERK VAN DER WOUDE.
